UNITED STATES PATENT OFFICE.

JOHN H. KETCHESON, OF ST. LOUIS, MISSOURI, ASSIGNOR OF ONE-HALF TO
JOHN M. GOMES, OF ST. LOUIS, MISSOURI.

PRINTING APPARATUS.

SPECIFICATION forming part of Letters Patent No. 743,884, dated November 10, 1903.

Application filed March 2, 1903. Serial No. 145,823. (No model.)

To all whom it may concern:

Be it known that I, JOHN H. KETCHESON, a citizen of the United States, residing at St. Louis, Missouri, have invented a certain new and useful Improvement in Printing Apparatus, of which the following is a full, clear, and exact description, such as will enable others skilled in the art to which it appertains to make and use the same, reference being had to the accompanying drawings, forming part of this specification, in which—

Figure 1 is a side elevational view. Fig. 2 is a sectional view of Fig. 1, taken on line 2 2 looking in the direction indicated by the arrows. Fig. 3 is a sectional plan view taken on line 3 3. Figs. 4, 5, 6, and 7 are detail views hereinafter described. Fig. 8 is a detached sectional detail of the hopper with its plunger in an elevated position, and Fig. 9 is a similar view with the plunger in its lowered position.

This invention relates to machines designed for the purpose of printing, marking, or stamping upon cylindrical or somewhat cylindrical articles, especially cigarettes, cheroots, cigars, and other articles manufactured from tobacco, the object of the invention being to produce such a machine which will be substantially automatic in its operation and sufficiently yielding in its coöperating parts to adapt itself to the variety of conditions which arise in the commercial use of mechanism of this character.

In marketing cigars it is desirable that some distinguishing mark shall be applied to each cigar for various reasons, and to apply such mark, brand, or emblem as will clearly distinguish such cigars the machine has been invented.

In the description and claims following where the terms "inking device," "inking-roller," "ink," &c., are used it should be understood that the same are used merely for brevity and convenience of description, and while it is possible that commonly known kinds of ink may be used it should be understood that I do not intend to limit myself to ink containing the ordinary pigment, but prefer to use some formula of marking mixture which will conform as nearly as possible to the particular requirements where the de-

vice is used in marking cigars or tobacco products.

Referring to the drawings, A is a frame of any suitable material, carrying the posts B, 55 which may be integral therewith or separately formed and secured thereto, as may be desired.

Projecting forwardly from the posts B are the brackets C, in which are carried operating parts hereinafter described.

1 is a hopper, into which the cigars are placed for convenient feeding to a conveyer hereinafter described.

The feed from the hopper, which is regulated by means of a reciprocating plunger 2, provided with an opening 3 therethrough, and the beveled head 4, is designed as a stop to close the exit-orifice 5 when desired. In line with the orifice 5 is a conveyer 6, provided with separating-blades 7, arranged at convenient intervals along the face of said conveyer to provide receptacles therebetween, in which are carried the cigars to be marked. On the shaft 8, upon which is carried the conveyer 6, is a ratchet 9, coöperating with the spring-actuating pawl 10, pivotally connected to the pivoted arm 11, which arm also actuates plunger 2 through the auxiliary arm 12 and rod 13, connected with said plunger 2. The rearward end of the conveyer is supported upon the shaft 14, which is yieldingly sustained in position by means of the spring 15 bearing against the boxes 16, in which said shaft 14 is supported, while 85 set-screws 17 and 18 are provided for the purpose of securing more or less vertical adjustment of the forward end of said conveyer, whereby the same coöperating with a die or marker traveling through a predetermined 90 zone may be brought into contact therewith regardless of the diameter of the cigars carried by the said conveyer.

In the post B is held a shaft 20, upon which is carried a driving-pulley 21, which may be 95 driven by any convenient connection and is preferably continuously rotating during the operation of the machine.

Carried on the shaft 20 is a gear 22, while either integral with said gear 22 or on a separate member is formed the cam 23. The gear 22 meshes with a pinion 24, which in turn

meshes with the pinion 25 upon the shaft 26, which shaft is provided with a spline or feather 27 and carries the distributing-cylinder 28, which cylinder projects slightly below the arc of the ink-plate 29, which is supported in any convenient manner, as by means of the brackets 30, from the lower arm C. Traveling over the ink-plate 29 and the projecting portion of the roller 28 are the inking-rollers 31, loosely mounted in the bracket 32 by means of the trunnions 33, held in bearings 34. The bracket 32 is pivotally connected to the rod 35, carried in the arm 36, and is yieldingly supported therein through the instrumentality of the spring 35^a, so as to permit more or less play of said rollers 31 in operation. The upper end of the arm 36 is pivotally supported upon the stud or shaft 37 and is provided with a vertically-projecting portion 38, to which is pivotally connected the link 39, to which in turn is pivotally connected the link 40, provided with the stud or roller 41, working in said cam-groove 23, so that as the said shaft 20 rotates it will carry with it the gear 22 and cam 23, thereby actuating the distributing-cylinder 28 and the said rollers 31.

Suitably mounted in the arm C is a reciprocatory plunger 42, carrying upon its lower face a die or marker 43, which is preferably dovetailed, so as to lock it in position in the lower end of the plunger 42, and is removable therefrom to permit the substitution of one marking-die for another when desired. Pivotally connected to the plunger 42 is a bracket 45, provided with an angular offset, to which is pivotally connected the end of the arm 46, which leads from thence rearwardly, where it is pivoted on the stud-shaft 47 and extends thence rearwardly, where its free end is provided with a roller 48, working in said cam-groove 23, so that as the said cam rotates the plunger 42 will be given a reciprocatory motion, whereby the die 43 on its lower end will be carried into contact with cigars or other articles, (indicated in dotted lines by the reference-letter a,) carried in the said conveyer 6. Supported by the bracket 50, connected, preferably, to the rear end of the frame A, is a pivoted link 51, which is likewise provided with a roller or stud 52, also held in said cam-groove 23, while another link 53 extends thence downwardly and is pivotally connected to the rear end of the lever 11, before referred to, through link 11^a, whereby upon each rotation of the cam 23 the plunger 2 and the pawl 10 will be actuated, thereby releasing one cigar from the hopper and advancing the ratchet 9 one tooth, and consequently with it the conveyer 6 one degree. Upon reference to Fig. 3 it will be seen that the ink-distribution cylinder 28 is substantially a shell or pulley, in the hub of which is formed the cam 55, while the arm 56, provided with a stud 57, is connected securely to the arm C, so that upon rotation of the ink-distribution cylinder 28 the stud following the cam-groove

55 will cause complete lateral thrust and return of the ink-distribution cylinder 28, whereby ink placed upon its surface will be the more perfectly distributed and thereby more evenly fed to the inking-rollers 31. Upon reference to Figs. 4, 5, 6, and 7 it will be observed that the conveyer 6 is composed of interlocked hinged sections connected by means of the pintles b, while the vertically-extended projections 7 of said conveyer are provided with the return-bend c, which is adapted the more firmly to hold in position the spring-clasp 60, which, by reason of its peculiar bend and the spring metal of which it is formed, will readily pass down over the said return-bend c and be thereby properly held in position against removal, except upon sliding the same longitudinally of said vertically-extending portions 7. The object of the members 60 is to provide some means for partially filling the spaces between the several members 7 when desired, as in the case of cigars or other articles smaller than the largest size marked by the machine being passed through the machine.

The operation of the machine is as follows: The hopper 1 being filled with cigars and the machine operated, it will be apparent that upon each rotation of the shaft 20 the plunger 2 will automatically descend and rise, whereby cigars will be fed to the conveyer until a sufficient quantity has been fed thereon to carry the most forward one underneath the printing-die or marker 43, which die, being controlled in its movement by said cam 23, will have imparted to it the necessary reciprocatory movement to cause it to rise and fall, carrying it upon each descent into contact with one of the cigars a, carried and firmly held by the conveyer 6, and to provide a convenient and necessary amount of ink to enable the die 43 to mark said cigars. The rollers 31 will be, through the means described, carried back and forth in contact with the ink-distribution cylinder 28, ink-plate 29, and die or marker 43, whereby the supply of ink or marking material will be constantly renewed upon the face of said die, the arm 11, carrying the pawl 10, meanwhile advancing the conveyer 6 step by step and supplying the cigars regularly to the marking-die. It will be apparent that an apron or other means may be provided upon which the cigars or other articles may fall from the conveyer 6 after being marked; but to avoid confusion it is not shown.

The vertical projections 7 are a part of or are rigidly fixed at right angles to the base and at one end of each link, so that while passing around the forward drum X said projections 7 will separate, thus allowing the cigars to fall freely into place between said projections 7 and to close upon and hold said cigars firmly when said links advance to the plane connecting the drums X and X' while said cigars are being carried to the printing device, and especially while said cigars are

being printed. Said projections will be separated as they pass over the drum X', thereby releasing the cigars after having been so stamped, whereupon they will fall upon an 5 apron or other device provided for their reception.

I am aware that minor changes in the construction, arrangement, and combination of the several parts of my device can be made 10 and substituted for those herein shown and described without in the least departing from the nature and principle of my invention.

Having thus described my invention, what I claim as new, and desire to secure by Letters 15 Patent, is—

1. In a machine for marking on cylindrical bodies, a reciprocatory plunger, marking-die thereon, an intermittently-operated inking-roller therefor, an intermittently-operated 20 feed-conveyer coöperating with said plunger, an actuating-cam, and connections between said cam, conveyer and inking-roller whereby said cam is caused to actuate the same; substantially as described.

2. In a machine for marking on cylindrical bodies, a marking-die normally at rest, an inking means coöperating therewith, an intermittently-operated conveyer, a cam for actuating said marking-die when said conveyer is 25 at rest, and means operable from said cam for actuating said inking means when said marker is at rest; substantially as described.

3. In a machine for marking on cylindrical bodies, a marking-die normally at rest, an inking means coöperating therewith when at rest, an intermittently-operated conveyer, and a cam for actuating said marking-die when said conveyer is at rest, and for actuating said conveyer when said marking-die is at rest; 30 substantially as described.

4. In a machine for marking on cylindrical bodies, a hopper, an intermittently-actuated feed therefor, a conveyer coöperating therewith, means for providing regularity of spacing on said conveyer, an intermittently-operated 35 plunger coöperating therewith, a marking-die on said plunger, and a cam operating said feed and said marking-plunger; substantially as described.

5. In a machine for marking on cylindrical bodies, a driving-shaft, an actuating-cam thereon, a reciprocatory marker and an intermittently-actuated conveyer coöperating with said marker, said conveyer and said marker 40 being connected with said cam so as to be actuated thereby; substantially as described.

6. In a machine for marking on cylindrical

bodies, a driving-shaft, marking means, means on said shaft adapted to impart reciprocatory motion thereto, a conveyer, spacing means 60 thereon and means detachably connected therewith for decreasing the minimum openings between said spacing means; substantially as described.

7. In a machine for marking on cylindrical bodies, an actuating means, a continuously-driven cam, a reciprocatory marker and inking means therefor, actuated by said cam, and an intermittently-operated conveyer actuated by said cam coöperating with said marker; 70 substantially as described.

8. In a machine for marking on cylindrical bodies, a driving-shaft, an ink-distribution cylinder driven thereby, a cam on said shaft, a reciprocatory plunger and an intermittently-actuated conveyer coöperating therewith, said plunger and said conveyer being driven from said cam; substantially as described.

9. In a machine for marking on cylindrical bodies, a driving-shaft, a cam on said shaft, 80 a marker and a conveyer both of which are actuated by said cam, and a yieldingly-supported inking-roller for inking said marker intermittently coöperating with said marker; substantially as described.

10. In a machine for marking on cylindrical bodies, a driving-shaft, an automatically-operated feeding means, intermittently-actuated conveyer, intermittently-operated marker, and a cam on said driving-shaft co-operating with said marker and said feeding means; substantially as described.

11. In a machine for marking on cylindrical bodies, a driving-shaft, an automatically-operated feeding means, intermittently-actuated conveyer, intermittently-operated marker, intermittently-operated inking means therefor, and a cam on said driving-shaft actuating said feeding means, said conveyer and said marker; substantially as described.

12. In a machine for marking on cylindrical bodies, a yieldingly-supported and intermittently-actuated conveyer, a reciprocatory marker, an actuating-cam, and actuating connections between said cam, said conveyer and marker; substantially as described.

In testimony whereof I hereunto affix my signature, in the presence of two witnesses, this 23d day of February, 1903.

JOHN H. KETCHESON.
